UNITED STATES PATENT OFFICE

HARRY GLAENZER, OF PHILADELPHIA, PENNSYLVANIA

THROTTLE FOR LOCOMOTIVES

Application filed November 19, 1931. Serial No. 576,145.

One object is to construct a throttle valve for locomotives in which a double seated valve is used to provide ample room for the passage of steam through the valve casing.

5 A further object of the invention is to provide conical valve seats for the valve.

A still further object of the invention is to make the lower portion of the arc of the valve heavier than the upper portion, so as 10 to counteract the tendency of the steam to force the lower face or edge of the valve from its seat, causing the valve to leak.

15 And a further object of the invention is to proportion the head which holds the valve ring or cage so that it will have a deep penetration in the valve casing, in order to provide a proper area for the flow of steam through the casing.

20 The valve-operating mechanism is of the standard type and forms no part of the present invention.

In the accompanying drawings:

Fig. 1 is a sectional elevation of the upper portion of my improved throttle valve, the 25 section being on the line 1—1, Fig. 2;

Fig. 2 is a sectional plan view on the line 2—2, Fig. 1;

Fig. 3 is an enlarged sectional view of the valve;

30 Fig. 4 is an enlarged detached sectional view of the valve seat;

Fig. 5 is a diagrammatic sectional view showing the upper flange of the valve seated on the upper valve seat; and

35 Fig. 6 is a diagrammatic sectional view showing the lower flange of the valve seated on the lower valve seat.

Referring to the drawings, 1 is the casing of the valve, having a steam inlet passage 2 40 at the upper end thereof and an outlet passage 3. The lower end of the valve casing is beveled at 4 so that it can be coupled to a steam pipe leading to the cylinders of the locomotive. The valve casing is located in the dome of the boiler in the ordinary manner. The outlet passage 3 extends entirely around the valve chamber and is connected to the valve chamber 5 by ports 6. 7 is the seat ring or cage having an upper shoulder 8 and 45 a lower shoulder 9. These two shoulders fit

corresponding shoulders on the valve casing. The seat ring has an upper section 10 and a lower section 11, the two sections being connected by a series of posts 12. This construction allows the steam to escape from the valve 55 chamber and through the ports 6 into the outlet passage 3. The seat is held in place by a head 13, which extends into the valve casing from the underside and is recessed at 14 to fit the lower member of the valve ring, as clearly shown in Fig. 1, and has a flange 15 at its lower end, through which the retaining bolts 16 extend, and on these bolts are nuts 17. The lower portion of the head has a comparatively loose fit in an internal flange on the 60 lower portion of the casing. Passages 19 in the head communicate with the annular space 65 20 between the cage and the casing.

The head is made hollow as shown and is closed at its upper end and has an extended 70 hub 21 connected to the outer portion of the cage by webs 22. Passing through the head is a valve stem 23, and secured to the upper end of this stem by a nut 24 is the valve 25. The valve has a hub 26, which fits the reduced 75 end 23a of the valve stem 23 and is connected by a series of arms 27 to the outer rim 28, which is substantially in the form of an arc, providing an annular passage for steam when the valve is in the open position.

It will be noticed in Fig. 3, that the lower portion of the arc of the rim of the valve is much heavier than the upper portion, so as to 80 counteract the tendency of the steam to force the lower valve face or edge away from its seat, which would cause it to leak. The upper and lower edges 29 and 30 of the valves are conical and fit against conical seats 31 and 32 of the seat ring 7, Figs. 5 and 6. The extension of the planes passing through the conical valve seats meet at the center line X of the valve, as shown by dotted lines in Fig. 3. This construction insures the accurate fitting the valves on the seat ring when in the closed position. The valve stem 23 is connected to the operating mechanism 33, common to locomotive throttle valves. The elevation of the valve is limited by a projection 34 on the shaft 35 coming in contact with an abutment 36 on the valve casing, Fig. 1.

When the valve is seated as shown in Fig. 1, the steam is entirely cut off from the outlet passage 3, but when the mechanism 33 is actuated by the engineer, the valve can be raised 5 to any point desired, so as to control the flow of steam from the dome of the boiler through the inlet passage 2, through the annular passage of the valve, and through the center of the valve to the outer passage 3. The arc of 10 the rim of the valve is of such depth that when the valve is full open the steam will freely flow past the valve into the outlet passage 3.

I claim:

1. The combination in a throttle valve, of 15 a casing having a valve chamber; an inlet passage and an outlet passage communicating with the said chamber; a seat ring mounted in the casing and surrounding the valve chamber, said ring having openings through its wall and having upper and lower seats; and a valve in said chamber, having a hub and rim and open at the center, the rim having upper and lower edges arranged to close against the seats, the rim being in 20 25 the form of an arc, the lower portion of the arc being of greater thickness than said upper portion thereof.
2. The combination in a throttle valve, of 30 a casing having a valve chamber therein; an inlet communicating with the valve chamber and an outlet also communicating with the chamber and extending around said chamber; a seat ring mounted in the casing and surrounding the valve chamber, the seat ring having openings through its wall and having upper and lower seats beveled in opposite directions; and a valve located in the chamber and having an opening through its center, the rim of the valve being in the form 35 40 of an arc, the upper and lower edges of the rim being conical to fit the beveled seats of the seat ring.

3. The combination in a throttle valve, of 45 a casing having a valve chamber therein; an inlet passage communicating with the chamber; an outlet passage extending around the valve chamber and lateral ports forming communication between the valve chamber and the outlet passage; a seat ring mounted in the valve casing and surrounding the valve chamber, the seat ring having upper and lower members and connecting posts; a valve mounted in the valve casing and open at the center, the rim of the valve being in 50 55 the form of an arc and having upper and lower conical edges fitting corresponding edges in the upper and lower edges of the seat ring, the lower portion of the valve being heavier than the upper portion thereof.
4. The combination in a throttle valve having a valve chamber therein; an inlet opening in the upper portion of the casing communicating with the valve chamber; an annular outlet passage surrounding the valve 60 65 chamber; ports connecting the passage with

the valve chamber; a valve seat ring mounted in the casing and surrounding the valve chamber and having openings through its wall, the valve casing having an opening under the seat ring; a head extending into the opening bearing against the seat ring, holding it in position in the casing; means for securing the head to the casing; a valve stem extending through the head; and a valve mounted on the stem within the valve chamber, the rim of the valve having upper and lower edges, the valve being open at the center, the upper and lower edges of the valve fitting the seats of the seat ring when in the closed position.

5. The combination in a throttle valve casing having a valve chamber therein; an inlet passage at the top of the casing and an annular outlet passage; lateral ports connecting the valve chamber with the outlet passage; a seat ring fitting shoulders on the valve casing and surrounding the valve chamber, said seat ring having upper and lower members and connecting posts; a deep head located in the lower portion of the valve casing and bearing against the underside of the seat ring; means for securing the head to the casing; a valve stem extending through the head; and a valve mounted on the stem and secured thereto, said valve having a hub and an arc shaped rim connected by arms, the upper and lower seating edges of the valve being conical, the extension of the plane passing through the seating edges of the valve meeting at the center line of the valve, the lower portion of the arc of the valve being heavier than the upper portion.
